UNITED STATES PATENT OFFICE.

ALFRED BAROLET, OF WICKFORD, RHODE ISLAND.

STOP MOTION FOR BRAIDING MACHINES.

Application filed October 4, 1923. Serial No. 666,479.

To all whom it may concern:

Be it known that I, ALFRED BAROLET, a citizen of the United States, residing at Wickford, county of Washington, State of Rhode Island, have invented certain new and useful Improvements in Stop Motions for Braiding Machines, of which the following is a specification.

This invention relates to improvements in braiding machines and particularly to machines for braiding elastic cords or fabrics.

The principal object of the invention is to provide improved means for delivering a plurality of elastic strands under tension to the braiding-mechanism, whereby they may be incorporated in the braid being produced on the machine.

Another object of the improvement consists in providing a multiple stop-motion adapted to be actuated upon the breakage of any one of the elastic strands to arrest the operation of the braiding machine.

Another object of the improvement is to provide for greater accessibility and convenience in applying the elastic strands to the machine and in piecing up the ends when a strand or strands become broken.

Further objects of the improvement are set forth in the following specification which describes a preferred embodiment of the invention, as illustrated in the accompanying drawings. In the drawings:

Fig. 1 is a side elevation of a conventional type of braiding machine, shown partly in section on its vertical axis, and illustrating my improvements as applied to use therewith;

Fig. 2, a part sectional elevation of a portion of the machine, showing the stopping-mechanism thereof, and illustrating my improved stop-motion as used in connection therewith;

Fig. 3, a sectional view of the clutch-mechanism of the machine shown in detail;

Fig. 4, a plan view of the stopping-mechanism control-lever and its detent arrangement;

Fig. 5, a detailed plan view of the knock-off mechanism of my improved stop-motion;

Fig. 6, a side elevation of the same.

Referring first to Fig. 1 of the drawings, 2 designates the circular bottom-plate or base of the braiding machine and 3 is the top-plate in which is provided a sinuous track or raceway 4 for the sliding bobbin-

carriers 5. The top-plate 3 is shown in section in Fig. 1 to illustrate the manner in which the shoes 7 on the carriers 5 travel in the raceway 4 with their flanges 8 overlapping the sides of the grooved track and abutting the top and bottom faces of the plate 3. Beneath the race-plate 3 are a series of horn-gears 10 journaled on studs 11 and arranged with their teeth in mesh to form a train in which alternate gears rotate in opposite directions. The horn-gears 10 are driven from a spur gear 12, see Fig. 2, which is rotated from a bevel-gear 14 connected thereto by a stud-shaft 15. The bevel-gear 14, in turn, is driven from another bevel-gear 16 which is rotated from a driving pulley 17 adapted to receive power from a belt 18.

Referring again to Fig. 1, the horn-gears 10 carry hooked horns 20 which engage with depending studs 21 on the carriers 5 whereby to traverse the carriers through the track or raceway 4. Through this arrangement the carriers 5 are revolved in opposite directions around the machine while being caused to follow sinuous courses to adapt them to dodge each other as they move in and out with respect to the axis of the machine. The carriers 5 carry yarn-bobbins 6 from which the strands 7 deliver through usual tension and let-off devices, indicated at 24 as being mounted on standards 25 rising from the carriers. The strands 7 lead through guides 26 in the top of the standards 25 and converge toward the braiding point 27 where they are enmeshed and consolidated in the braided cord or fabric C.

The arrangement of the machine as so far described is common to braiders of a well known type, and usually a clutch-device is provided for controlling the operation of the braiding-mechanism. The clutch-mechanism may be of any suitable form and, as shown in Figs. 2 and 3, comprises a slidable clutch-member 30 which is held rotatively with the stud-shaft 15 on which are carried the gears 12 and 14. The spur-gear 12 is secured fast to the shaft 15 by means of a set-screw 31 in its hub, see Fig. 3, whereas the bevel-gear 14 is free to rotate on said shaft except when engaged by the clutch-member 30 which connects it thereto. For this purpose the clutch-member 30 is held rotatively with the shaft 15 by means of a collar 34 fast thereon, being provided with lugs or spurs 32 adapted to engage with slotted openings 33 in the collar 34 and with

lugs 29 on the hub of the gear 14. The clutch-member 30 is held in engagement with the gear 14 by means of a control-lever 35 provided with a hub surrounding the shaft 15 and formed with a boss 36 which bears against the lower end of the clutch-member. The lever 35 is formed with a hooked extremity 37 held in an opening 38 in a depending arm 39 which is supported from the framework of the braiding machine and reaches down with its right-angled end 40 abutting the lower end of the shaft 15.

At the opposite end of the lever 35 is a handle 41 for operating the clutch manually, and a link 43 pivoted to the lever 35 at 44 extends upwardly to engage with a detent-lever 45. The link 43 is formed with a hook or catch 46 adapted to hook over the edge of the detent-lever 45, as illustrated most clearly in Figs. 2 and 4. The detent-lever 45 is of a general fork-shape and is pivoted at one end on a stud 47 held in the edge of the top-plate 3 of the machine framework. The lever 45 is operated to effect automatic control of the stop-mechanism by means of a link 48 having a pin 49 engaging a slot 50 in one of its forked arms. The opposite end of the link 48 is pivoted at 51 to a vertically disposed lever 52 which is controlled from the stop-motion for the elastic strands in the manner and for the purpose as later described.

As shown in Fig. 1, the lever 52 is pivoted on a screw 53 screwed through a block 55 into a vertical standard 56 which rises from the framework of the machine at one side of the braiding-mechanism. The standard or upright 56 carries a framework 60 at its upper end, on which is supported the supply-spool S for the elastic strands s. As shown in Figs. 1 and 2, the framework or bracket 60 comprises two upright arms 61 mounted on a cross-bar 62 at the top of the vertical standard 56, and connected by cross-rods 63, 64, 65 which are held therein by set-screws 66. At the upper end of the arms 61 are socketed bearings 67 for receiving the ends of the mandrel or spindle 68 on which the spool S rotates. Extending between the arms 61 of the bracket 60 are two closely-spaced parallel rods 70 and 71 beneath which the elastic strands s draw as they lead down from the barrel of the spool S. From the rearward rod 71 the strands lead around a third rod 72, also supported between the arms 61, and thence down around a roller 75 which is journaled in bearing-arms 76 bolted to the under side of the base-plate 2 of the machine. From the roller 75 the strands lead beneath the base-plate 2 where they are severally guided under individual guide-pins which direct them to appropriate positions whence they lead upward through the braiding-mechanism.

As shown in Figs. 1 and 2, several of the strands s lead under parallel guide-pins 77 mounted on a yoke-shaped bracket 78 secured to a framework 79 which is supported beneath the base-plate 2. Certain of the strands s lead from the guide-pins 77 to auxiliary guide-pins 80, 81 and 82, and thence are directed upwardly to the braiding-mechanism, each strand having a guide-pin located in appropriate position to direct it upwardly through an axial opening in one of the horn-gears 10. Fig. 2 shows the lower framework 79 in section so that only one-half the whole number of guide-pins is illustrated in this view, it being understood that in the present machine the arrangement is such as to provide for incorporating eight elastic strands in the braid. Any suitable number of strands of yarn may be braided into the fabric, the whole number being determined by the number of bobbin-carriers 85 used on the machine.

In Fig. 2 of the present drawings the machine is shown in section on its vertical axis and only five of the bobbin-carriers are illustrated; but it is to be understood that the number may vary in accordance with the type of braid being produced. Likewise, a greater or less number of elastic strands may be incorporated in the braided fabric, but as here shown the machine is equipped for eight strands, with a single strand passing up through the axis of each one of the horn-gears 10. As the machine is shown in section in Fig. 1, only four of the elastic strands s are illustrated and these pass up through the axial openings in the horn-gears 10 and thence draw up through guides 83 at the upper ends of standards 84 mounted on top of the race-plate 3. From the guides 83 the elastic strands s draw to the braiding point x where they are merged in the fabric as it passes through the gatherer 85. It will thus be seen that as the elastic strands s are drawn through the center of the circular quoits 86, which define the loop portions of the raceway 4, the bobbin-carriers 5 are caused to travel around the individual elastic strands to entwine the yarns y therewith. This arrangement of the braiding-mechanism is common to braiders of the present type, and being well known in the art needs no further description. Suffice it to state that the supply-spool S for the elastic strands is placed above the braiding-mechanism in order to be convenient of access in feeding the strands to the machine and in providing for piecing up the ends when the strands become broken. The improved means for directing the strands to the braiding-mechanism forms an important feature of the present invention.

My improved stop-motion for controlling the operation of the machine from the delivery of the elastic strands is constructed

and arranged as now described. Pivotally mounted on the forward cross-rod 63 which extends between the arms 61 are a series of drop-levers or sentinels 88, one for each elastic strand *s*. The levers 88 are of bell-crank shape with horizontal arms 89 carrying hooked wires 87 at their ends adapted to hook under the strands *s* as they lead between the two tension-rods 70 and 71, see Fig. 1. The arms 89 when their wires 87 are hooked under the strands *s* rest against the cross-rod 64 with the opposite arms 90 of the levers 88 extending slightly away from the perpendicular. The arms 90 are much heavier than the arms 89 and thus act as weights to swing the drop-levers 88 downwardly when the hooks 87 on the arms 89 are released by the breaking of the strands *s*. In Fig. 1 the normal position of the drop-levers 88 is shown by full lines, while the dotted lines in this view indicate the position to which the drop-levers fall when the hooks 87 on the arms 89 are released. The weight-arms 90 of the drop-levers 88 are adapted to strike against a cross-bar 92 forming a part of a movable knock-off frame 93 which acts as the deterrent-means for restraining the movement of the pivoted lever 52 which operates the stopping-mechanism of the braiding machine. As shown in Figs. 5 and 6, the frame 93 comprises two arms 94 having pins 95 at their inner ends mounted to slide in openings 96 in the cross-bar 62 at the top of the vertical standard 56. The arms 94 rest across the top of a rod 97 which is slidable in bearings 98 in the upright arms 61 of the bracket 60. The movable knock-off frame 93 is urged outwardly by coiled springs 99 surrounding the pins 95 between the cross-bar 62 and the right-angled ends of the arms 94 of the frame; the heads of the pins 95 being adapted to strike against the rod 97 to act as a stop to limit the sliding movement of the frame. In one of the arms 94 is a downwardly-extending detent-pin 100 which is adapted to engage with a slot 101 cut through the top of the sliding rod 97. The rod 97 is pivotally connected to the upper end of the rockable lever 52 by means of a stud or pin 103, and is normally urged to the right, as viewed in Figs. 2 and 5, by means of a coiled spring 104 surrounding its outer end. The spring 104 is adapted to be compressed between the side of the arm 61 of the bracket 60 and a washer 105 fastened to the end of the rod 97 by means of a screw 106. When the braiding machine is operating under normal conditions the lever 52 is held in vertical position with the rod 97 slid to the left, as viewed in Figs. 2 and 5, to compress the spring 104; the rod 97 being maintained in this position by the detent-pin 100 engaging the slot 101 in the rod. When the frame 93 is slid

to the left, as viewed in Fig. 6, this action being caused by the dropping of any one of the drop-levers 88, the pin 100 is released from the slot 101 and the rod 97 is thereby allowed to be slid to the right under the action of its spring 104, as indicated by the dotted lines in Fig. 2. This sliding movement of the rod 97 rocks the lever 52 to swing the detent lever 45 to release the clutch in the manner and for the purpose as later more fully explained.

The method of operation of the complete apparatus is as follows: The braiding machine is prepared for operation by mounting the bobbins *b* on their carriers 5 and leading their strands *y* up to the braiding point *x*. The spool *S* for the elastic strands *s* is placed on its mandrel 68 and the latter mounted in the socketed bearings 67 at the top of the arms 61 of the bracket 60. The strands *s* from the spool *S* are then drawn down under the tension-rods 70 and 71, and around each strand is hooked the wire 87 at the end of the arm 89 of the appropriate drop-lever 88. The elastic strands *s* are then drawn down across the rod 72 and roller 75, and after being carried around their appropriate guide-pins are led up through the axial openings in the horn-gears 10 and quoits 86 to the guides 83 at the top of the standards 84. Thence the elastic strands *s* are led to the braiding point *x* and the machine is ready to be operated, all of the strands being first twisted together and drawn up through the take-up device, a portion of which is indicated at 110 in Fig. 1.

To start the machine the clutch-control lever 35 is raised to slide the clutch-member 30 upwardly on the shaft 15 whereby to engage its spurs 32 with the lugs 29 on the hub of the gear 14. The gear 14 will thus be caused to rotate the shaft 15 to drive the spur-gear 12 which transmits rotation to the horn-gears 10, it being understood that the bevel-gear 14 is continuously driven from the bevel-gear 16 which is rotated from the driving-pulley 17.

As the lever 35 is raised to operate the clutch-mechanism the link 43 will be slid upwardly to hook its catch 46 across the edge of the detent lever 45, it being noted that the lever 45 will be in the position illustrated in Figs. 2 and 4 when the lever 52 is in vertical position with its control rod 97 held by the detent-pin 100. This position of the detent-lever 45 is effected by carrying the rod 97 to the left, as viewed in Fig. 2, to allow the detent-pin 100 to engage its slot 101 after the elastic strands have been threaded into place to support the drop-levers 88 in raised position.

Now as the machine operates to braid the cord or fabric *C* the elastic strands *s* will be drawn off from the spool *S* and will be

tensioned to the required degree as they pass under the rods 70 and 71, across the rod 72, down under the roller 75, and thence to their respective guide-pins. As the strands 5 lead through the hooks 87 at the extremities of the arms 89 of the drop-levers 88 they maintain the weighted arms 90 of said levers in raised position, as shown by full lines in Figs. 1 and 2; but should a strand 10 break or become exhausted its respective lever 88 will be released to drop into the position indicated by the dotted lines in Fig. 1. As the drop-lever 88 turns into this position under the effect of gravity its 15 weighted arm 90 will strike against the cross-bar 92 on the frame 93 with sufficient force to slide the whole frame to the left, as viewed in Fig. 6, against the action of its springs 99. This sliding action 20 of the frame 93 will release the detent pin 100 from the slot 101 in the rod 97 whereby to allow said rod to slide to the right, as viewed in Figs. 2 and 5, under the action of its spring 104. 25 This sliding action of the rod 97 will rock the lever 52 to the position illustrated by the dotted lines in Fig. 2, and through its link 48 connected to the detent-lever 45 will swing the latter on its pivot 47 to cause it to 30 release the detent-link 43.

The release of the link 43 allows the control-lever 35 to drop so that it releases the clutch-member 30 which, under the action of gravity, will slide downwardly on the 35 shaft 15 to disengage its spurs 32 from the lugs 29 on the hub of the gear 14. The gear 14 will thus be freed from driving connection with the shaft 15 so as to be rendered inoperative to drive the machine. In this way 40 the operation of the machine is arrested immediately any one of the elastic strands becomes broken or exhausted so that the braiding action will be discontinued to prevent faults in the fabric through lack of the 45 proper number of strands.

Separate stop-motions are usually provided for the individual bobbin-carriers and are arranged to operate in connection with the clutch-mechanism of the machine as 50 herein shown, so that the braider may be brought to a stop upon the breaking of any one of the yarn strands leading from the bobbins on the carriers. The whole machine is thus maintained under complete control to 55 prevent faulty operation without the full number of strands being incorporated in the braided product.

It will be observed that my invention provides a most convenient arrangement for 60 mounting the supply of elastic strands on the braider, and one in which the several strands leading from the supply spool are at all times exposed for inspection and easily accessible for piecing up the ends. Furthermore, my improvement provides a

simple and efficient stop-motion which acts promptly and positively to arrest the operation of the machine upon the breakage or exhaustion of any one of the strands. The drop-levers or sentinels for the several elastic strands are arranged in position above the braiding-mechanism so as to be easy of access, to provide for more expeditious piecing up of the ends and setting of the stop-motion parts. The whole device is 70 particularly simple in construction and proof against derangement or getting out of order and is adapted to be attached to machines of standard type without alteration of the usual equipment and without 75 requiring extensive machining operations or 80 special fitting of the parts.

While I have herein shown one preferred embodiment of my improved apparatus, it is 85 to be understood that various modifications may be made in the structure and arrangement thereof without departing from the spirit or scope of the invention. Therefore without limiting myself to the exact arrangement shown, I claim:

1. In a braiding machine, the combination with the braiding-mechanism comprising revolving bobbin-carriers carrying yarn-supplies and means to traverse said carriers around the machine to interlace the yarns in the braided fabric, of means for supporting a supply-spool of elastic strands above the braiding-mechanism, means for tensioning said strands as they deliver from the spool, means for leading the strands 95 downwardly beneath the braiding mechanism, and means for individually directing the strands upwardly through the braiding mechanism in appropriate positions to adapt them to be braided into the fabric. 100

2. In a braiding machine, the combination with the race-plate thereof having a raceway, bobbin-carriers slidable in the raceway, means to propel the carriers through the raceway to cause the yarns from the bobbins to be interlaced in the braided fabric, of a standard extending upwardly from the race-plate, a supply-spool for elastic strands rotatably mounted on the standard, tension-means on the standard for applying tension to the strands, means to direct the strands downwardly from the tension-means and inwardly beneath the race-plate, and means for individually guiding the strands upwardly through the race-plate in appropriate positions to be enmeshed in the fabric. 115

3. In a braiding machine, the combination with the race-plate thereof having a raceway, bobbin-carriers slidable in the raceway, means to propel the carriers through the raceway to cause the yarns to be interlaced in the fabric, of a standard extending above the race-plate, a supply-spool 125 for elastic strands rotatably mounted on the 130

standard, means for directing the strands from the spool downwardly beneath the race-plate, a framework depending from the race-plate, and a plurality of separate guides on the framework for directing the strands upwardly through the race-plate in appropriate positions to adapt them to be enmeshed in the braid.

4. In a braiding machine, the combination with the braiding-mechanism comprising revolving bobbin-carriers carrying yarn-supplies, and means to traverse said carriers around the machine to interlace the yarns in the braided fabric, of means for supporting a supply-spool of elastic strands above the braiding-mechanism, means for tensioning said strands as they deliver from the spool, means for leading the strands downwardly beneath the braiding-mechanism, means for individually directing the strands upwardly through the braiding-mechanism in appropriate position to adapt them to be braided into the fabric, a series of drop-levers supported from the elastic strands, stopping-mechanism for arresting the operation of the braiding-machine, and means actuated from the falling of a drop-lever to cause action of the stopping-mechanism.

5. In a braiding machine, the combination with the braiding-mechanism comprising revolving bobbin-carriers carrying yarn-supplies, and means to traverse said carriers around the machine to interlace the yarns in a braid, of a standard projecting above the braiding-mechanism, a supply-spool for elastic strands supported on said standard, tension-means for the strands mounted on the standard, means for leading the strands downwardly beneath the braiding-mechanism,

nism, means for individually guiding the strands upwardly through the braiding-mechanism in position to be braided with the yarn strands, a series of drop-levers pivoted on the standard to adapt them to engage individually with the elastic strands at points adjacent the tension-means, stopping-mechanism for the braiding machine, and means actuated from the falling of a drop-lever to cause operation of the stopping-mechanism.

6. In a braiding machine, the combination with the braiding-mechanism comprising revolving bobbin-carriers carrying yarn-supplies and operating to interlace the yarns therefrom in the braided fabric, of means for supporting a supply-spool of elastic strands above the braiding-mechanism, tension-means arranged beneath the supply-spool with the elastic strands drawing thereover to apply tension thereto, means to lead the strands from the tension-means downwardly beneath the braiding-mechanism, means to guide the elastic strands upwardly through the braiding-mechanism in position to be braided with the yarn strands, drop-levers arranged beneath the supply-spool and having means engaged by the elastic strands as the latter draw through the tension-means, stopping-mechanism for the braiding machine, and means operated by the falling of a drop-lever upon the breakage or exhaustion of an elastic strand to effect the operation of the stopping-mechanism.

In testimony whereof I affix my signature.

ALFRED BAROLET.
